UNITED STATES PATENT OFFICE.

JOHN WALLACE NEFF, OF EASTON, PENNSYLVANIA.

DESIGN FOR ORNAMENTED PAPER.

Application filed August 18, 1927. Serial No. 23,141. Term of patent 3½ years.

To all whom it may concern:

Be it known that I, JOHN WALLACE NEFF, a citizen of the United States, residing at Easton, Pennsylvania, have invented a new, original, and ornamental Design for Ornamented Paper, of which the following is a specification, reference being had to the accompanying drawing, forming part thereof.

The figure is a plan view of a portion of a sheet of ornamented paper showing my new design.

I claim:

The ornamental design for ornamented paper as shown.

JOHN WALLACE NEFF.
